ville, Mich., a corporation of Michigan

Application October 18, 1944, Serial No. 559,186

8 Claims. (Cl. 292—332)

This invention is directed to a latch which has been designed for use on refrigerator doors, though of course not limited solely to such use. The provision of a simple and sturdy construction of latch, for the effective closing and tight sealing of a door accomplished in a novel and practical way, with a closing of the door by a light pressure, and with more effective overcoming of the resistance of the resilient gasket between the door and door casing are among the objects and purposes of the present invention.

Moreover, the latch construction is made largely of sheet metal parts which are readily and economically produced in quantity whereby the cost of the latch construction is low. The present latch construction and the embodiments illustrating the invention are, in a large measure, directed to the same objects and purposes as described in my recently filed application, Ser. No. 547,374, filed July 31, 1944.

An understanding of the invention may be had from the following description taken in connection with the accompanying drawings, in which,

Fig. 1 is a fragmentary horizontal section through the latch of my invention in closed position engaging with a latch bolt keeper, the keeper being fixed upon the refrigerator casing and the latch mounted upon the door.

Fig. 2 is an end elevation of the latch mechanism with the supporting sides therefor in section.

Fig. 3 is a section, similar to that shown in Fig. 1, with the latch bolt occupying the position which it has when the door on which it is mounted is opened, the pivotally mounted latch bolt being held in a cocked position.

Fig. 4 is a plan of the interior latch mechanism shown in Fig. 1, the supporting sides being shown in section.

Fig. 5 is a perspective view of the latch mechanism in the position which it occupies when a door is closed, the outer housing support therefor being indicated in dotted lines.

Fig. 6 is a section of a latch mechanism, similar to that shown in Fig. 1, in a slightly modified form but having structure operating in the same manner and upon the same principles of operation.

Fig. 7 is a view similar to that shown in Fig. 2, a partial section and end elevation of the latch, 50 and

Fig. 8 is a perspective view of the pivoted latch bolt shown in Figs. 6 and 7.

Like reference characters refer to like parts in the different figures of the drawings.

The latch of my invention is used in cooperation with a keeper which is secured at the front edge of a refrigerator or other casing, shown at 1, and the keeper is mounted upon a relatively heavy plate 2 of metal as shown. The keeper comprises a bracket 3 attached to the outer face of the plate 2, said bracket being of angle form, and to its outwardly extending leg the immediate keeper member is connected. Said immediate keeper member is bent from a single length of metal with an intermediate section 4, which is secured to the bracket 3, a ledge 5 turned from one end of the section 4 with which the latch bolt engages, and a trip finger 6 turned in the same direction as the ledge 5 and spaced therefrom as shown in Figs. 1 and 3.

The door 7 of the refrigerator which is hingedly mounted in the usual manner for closing the refrigerator open side and for opening to gain access to the contents of the refrigerator has, at its inner side, a plate 8 usually of non-metallic material with an opening 9 therethrough covered by a thin plate 10 with a smaller opening 11. Through said openings 9 and 10 the keeper or strike previously described passes to the interior of the door when the door is closed. The disclosure of the latch structure shows it semi-concealed within the door, the operating handle therefor being mounted at the outer side of the door, but the invention is not to be considered as restricted solely to concealed latch installation.

The outer side 12 of the door is of a usual and conventional shape and form and connected with the remaining parts of the door in accordance with well known practice. The door, at its inner side and around its outer edges, is provided with a cushioning compressible gasket 13 usually of rubber or similar material which when the door is closed and held in tightly closed position, is compressed and maintains a tight seal between the door and door casing or jamb to avoid entrance of heat which serves to decrease the efficiency of the refrigerator. Also, as shown in Fig. 45 1, a relatively heavy supporting plate 14 of the shape shown is made a part of the door being concealed back of the outer side 12 and connected at one end by brackets 15 together with inner and outer plates 16 and 17, one of which lies at the inner side of the outside member 12 of the refrigerator and the other at the outer side thereof. Screws are used to connect the two plates together, said screws at one edge of the plate also being utilized to secure the bracket 15 in place. 55 The plates 16 and 17 have oppositely disposed

sleeve guides 18 for a latch operating rod 19 which passes through and is guided by said sleeves and at its inner end portion passes through an opening in the plate 14 to engage with a suitable part of the interior latch mechanism to actuate the same when the rod is forced inwardly.

A handle 20 for manual operation is pivotally mounted between its ends on brackets 21 extending outwardly from the outer plate 17 being normally spring actuated by spring 22 to swing in a counter-clockwise direction about its pivot. Said handle has a ledge 23 against which the outer end of the rod 19 bears, whereby on pulling outwardly on the handle, the rod 19 is moved inwardly. The usual decorative covering or housing (not numbered) is used in connection with the inner end of the handle and parts associated therewith as shown. Such operating handle structure including a rod similar to the rod 19 for latch actuating is old and well known and is not in itself any part of the present invention.

The latch construction concealed within the door is mounted upon the plate 14. It includes a housing of sheet metal having spaced parallel sides 24 integrally connected at their inner edges by an inner side 25 which is inclined at an acute angle to the general vertical plane of the door. The sides 24 of the housing at their outer edges are turned outwardly to provide flanges 28 with suitable slotted openings therein (Fig. 4) for the passage of screws for connection to the supporting plate.

Adjacent to what may be termed the inner ends of the sides 24 of said housing, a cross rod 27 is mounted, being riveted over at its ends and lying between the sides 24. A flat bar 28 is provided with a slot 29 adjacent its inner end, the rod 27 passing through said slot. In practice rod 27 is provided with spacing sleeves, the two innermost of which come at their adjacent ends against opposite sides of the bar 28. A rod 30 extends transversely through the opposite or outer end of the bar 28, having heads 31 at opposite ends at the outer sides of the sides 24 of the housing. Said shaft, at its end portions, passes through slots 32 made in the housing sides 24, said slots 32 being equal in length and parallel to the side 25 of the housing. On the shaft 30 at each side of the bar 28 rollers 33 are mounted which are adapted to ride against the inner side of the housing side 25 and which, preferably, in practice will be formed integral with sleeves extending inwardly toward each other, the free ends of the sleeves coming against the opposite sides of the bar 28. The rollers 33 however are spaced at their outer sides a distance from the inner sides of the sides 24 of the housing and therefore are spaced from the heads 31. A relatively heavy coiled spring 34 is positioned around the bar 28, one end bearing against the rod 27 or the spacing sleeves thereon, and its opposite end against shoulders, as shown, near the outer end of said bar 28. Said spring normally tends to move the bar 28 to the left to the position shown in Fig. 1 or until stopped by the engagement of the rod 27 with the outer end of the slot 29.

The latch bolt is made from sheet metal having two spaced sides 35 integrally connected at their inner ends by a cross bar 36 and adjacent their outer ends by a cross member 37 but extending a distance beyond the cross member 37 and carrying a roller 38 between their free ends. The sides 35 are shaped with inner substantially straight sections and toward their outer ends are extended at an angle as shown so that each of

the sides 35 of the latch bolt is in effect a bent lever having two sections lying at a somewhat obtuse angle to each other.

Between the sides 35 a transverse rod is disposed upon which a roller 39 is mounted, said roller being adapted to bear against rollers 33. The latch bolt is normally spring actuated by a spring 40 mounted upon the rod 27 to turn in a clockwise direction and maintain the roller 39 in engagement with the rollers 33. The inner end of the rod 19, previously described, bears against a cross ledge 41 integral with and connecting outwardly extending arms of a bell crank lever 42, the other arms of said lever extending to the shaft 30 and being formed at their free ends with curved shoes 43 bearing against the rod 30 (Fig. 5). This bell crank lever construction is mounted upon a rod 44 extending between the sides 24 of the latch housing and is actuated by a spring 45 which maintains the ledge 41 in engagement with the end of the rod 19.

In Figs. 6, 7 and 8 a slightly modified construction is shown. The latch housing is the same with the spaced sides 24, but the inner side 25 is reduced in length as indicated at 25a in Fig. 6, and flanges 25b are turned inwardly toward each other beyond said inner side 25a. The shaft 30 carries rollers 33a spaced a short distance from rollers 33 riding against the inner sides of the flanges 25b (Fig. 7).

The bell crank levers 42 are closer spaced with the arc shaped bearing shoes 43 thereof located one at each side of the bar 28 and, therefore, bear against the sleeves which extend inwardly from the rollers 33. The latch bolt is substantially the same as previously described except that the sides 35a thereof are slightly different in shape. At the inner side of each of said sides 35a, an angle abutment 46 (Fig. 8) is permanently secured by spot welding. The upper sides of the inwardly extending legs of which bear against the rollers 33, being normally held in contact by spring 40. Such abutments 46 take the place of the roller 39 and serve the same purpose in the same manner as will hereinafter appear in the description of the latch operation.

When the door is in closed position, as in Fig. 1, the heavy spring 34 has moved the bar 28 to its extreme movement or until stopped by the rod 27. The rollers 33 bearing against the roller 39 swing the pivoted bolt in a counterclockwise direction, pressing roller 38 against the keeper ledge 5 and the gasket 13 is compressed between the door and the door frame or jamb.

On opening the door the handle 20 is swung outwardly about its pivot to move the rod 19 inwardly and turn the bell crank lever 42 in a clockwise direction, the shoes 43 at the inner ends of the levers pressing against shaft 30 in the construction shown in Fig. 5, and against the sleeves or rollers 33 on said shaft in the construction shown in Fig. 6, compressing the spring 34 and moving bar 28 to the position shown in Fig. 3. Spring 40 maintains the roller 39 or the abutments 46 in engagement with the rollers 33 and said rollers 33 or abutments 46 follow around the edges of the rollers 33 with a clockwise turning movement of the latch bolt until when the final position, as indicated in Fig. 3, the center of the rod 30 on which roller 39 is mounted passes within a line joining the axes of rods 30 and 27, thereby maintaining the latch bolt in a cocked position. The same action occurs with respect to the modified structure shown in Fig. 6, the points of engagement of the abutments 46 with the roll-

ers 33 being carried to a point above a line joining the axes of the rods 30 and 27. The door being opened by the outward pull on the handle, the roller 38 swings away from the ledge 5 and is moved outwardly beyond the free edge thereof so as to disengage from the keeper and permit the door to be swung fully open.

On closing the door with the pivoted latch bolt in its cocked position (Fig. 3), roller 38 strikes against the trip finger with a movement of the latch bolt in a counterclockwise direction. As soon as the axis of the rod carrying roller 38 passes by the line joining the axes of rods 30 and 27, spring 34 causes rollers 33 to ride upon the rollers 39 to the position shown in Figs. 1 and 5, roller 38 traversing the adjacent side of the finger 6 and then moving away therefrom and engaging the ledge 5 to pull the door into closed position and compress the sealing gasket. The same operation occurs in the construction shown in Fig. 6, the only difference being in the shape of the abutments 46 and rollers 33a, but both being engaged in a rolling contact by the rollers 33a with flanges 25b and rollers 33 with abutments 46.

While the force of the spring is decreased as it is extended in moving the bar 28 and rollers 33 from the position shown in Fig. 3 to that in Fig. 1, the distance through which the force acts in comparison to the distance that the latch bolt is swung progressively increases so that at the final closing of the door to the position shown in Fig. 1, there is in effect the same as an action of a lever of the first class, wherein the force or power is applied to a substantially fixed power arm of the lever but the weight arm of the lever is progressively decreased; and while the power applied to the power arm of the lever is somewhat decreased it is not decreased in the same proportion as the decreasing length of the weight carrying arm. Thus the effective force on the gasket to compress it progressively increases notwithstanding the fact that the force of the spring 34 is itself decreased as it elongates. This provides for a very effective action in sealing the refrigerator against refrigeration losses. The initial compression of the gasket requires less force than at the final stage of compression and with my invention such final heavier compression of the gasket is attained.

It should be noted that, in case the door is open, and the latch bolt becomes disengaged from its cocked position, in closing the door the roller 38 strikes against the outer side of the ledge 5 and springs 40 will yield and permit a swinging movement of the latch bolt, thereby insuring against damage which might occur if the latch bolt was fixedly secured against movement.

The invention is very practical and useful, readily manufactured in an economical manner and is of a strong and sturdy character. The claims appended hereto define the invention which is to be considered comprehensive of all forms of structure coming within their scope.

I claim:

1. A latch structure comprising, a housing support having spaced apart sides connected by a third side extending between said spaced apart sides, said third side lying at an acute angle to the planes of said spaced sides, and said spaced sides adjacent one end having slots therein in substantial parallelism to said third side, a bar located within the housing, a rod extending between the spaced sides of said housing, said bar having a slot therein generally paralleling the third side of the housing through which said rod

passes, said rod being located adjacent the ends of said spaced sides of the housing opposite where said slots in said sides are located, a rod extending through the opposite end of the bar and through the slots in the spaced sides of the housing, a roller on said last mentioned rod adapted to ride against the inner side of said third side of the housing, a coiled compression spring around said bar between the first mentioned rod and the opposite end portion of the bar, a latch bolt pivotally mounted on the first mentioned rod, said latch bolt being in the form of a bent lever having two sections disposed generally at an obtuse angle to each other, abutment means on said latch bolt bearing against said roller on the second mentioned rod, and spring means yieldingly acting on the latch bolt to move said abutment means against the roller, said latch bolt extending beyond said abutment means and having means at its free end adapted to engage with a keeper.

2. A construction as defined in claim 1, and pivotally mounted bell crank operating means located between the spaced sides of said housing and mounted thereon, at one end bearing against said second mentioned rod, and manually operable means bearing against the other end of said bell crank lever means for operating it, compressing the spring around said bar and changing the position of said roller relative to said abutment means.

3. A latch structure comprising, a support having spaced apart connected sides and a third side connecting the spaced sides at one of their edges, said third side being located at an acute angle to the length of the spaced sides and said spaced sides adjacent one end thereof and a short distance from said third side, each having a slot therein generally paralleling said third side, a rod mounted on and extending between said spaced sides adjacent the opposite ends thereof, a second rod extending between said spaced sides and at its end portions adapted to traverse said slots, rollers on said second rod riding against the inner side of the third side of said housing, spring means normally acting on said second mentioned rod to move it in one direction to the outer end of said slots, a latch bolt pivotally mounted at one end adjacent the inner ends of the spaced sides of the housing and located therebetween, said latch bolt being generally in the form of a bent lever having two sections lying at an angle to each other, and abutment means carried by said latch bolt between its ends bearing against said rollers, said latch bolt extending beyond said abutment means and the rollers and at its free end having keeper engaging means.

4. A construction having the elements defined in claim 3, and manually operable means engaging against said second mentioned rod to move it along said slots and compress the spring means acting thereon, thereby moving said rollers with relation to said abutment means, and means acting on said latch bolt to swing the bolt about its pivotal mounting and maintain said abutment means in contact with said rollers, as described.

5. In a latch structure, a housing support therefor having spaced apart sides and a third side connecting said sides at one edge thereof, said third side being located at an angle to the length of the spaced sides, a latch bolt located between the spaced sides of the housing and pivotally mounted at one end thereof adjacent one end of said spaced sides, a spring actuated bar

pivotal and slidably mounted to turn about the same pivotal axis as the latch bolt, rollers carried by the opposite end of the bar riding against the inner side of the third side of the housing, bearing means on said latch bolt to press against said rollers, spring means for maintaining the latch bolt in a position to hold said bearing means thereon in pressing engagement against said rollers, and manually operable means for moving said spring actuated bar against the spring actuating force thereof, as and for the purposes described.

6. In a latch structure, a housing support having spaced sides and a connecting third side at one of the edges thereof, said third side being located at an angle to the length of the spaced sides, and said spaced sides adjacent one end thereof and a short distance from the third side having longitudinal slots located in substantial parallelism to said third side, a rod extending between said spaced sides of the housing adjacent the end thereof opposite the ends where said slots are located, a bar having a longitudinal slot therein extending in the same direction as the slots in the sides of said housing through which said rod passes, a second rod extending through the opposite end of the bar and through the first mentioned slots in the housing sides, rollers on said last mentioned rod riding against the housing support, spring means on said bar normally moving it to carry said rollers to an extreme of movement in one direction, guided by the slots in the housing spaced sides, a latch bolt having

two spaced sides connected by spaced apart cross members one adjacent each end of said sides of the bolt, said bolt being pivotally mounted at one end on the first mentioned rod, said sides of the latch bolt being generally in the shape of a bent lever having two sections located at an angle to each other, bearing means carried by the sides of said latch bolt located in one position thereof against said rollers substantially opposite where said rollers bear against the third side of the housing, spring means acting on said latch bolt to yieldingly hold said bearing means against the rollers, and a keeper engaging roller located between the free ends of the sides of the latch bolt.

7. A construction having the elements defined in claim 6, a third rod located between the spaced sides of the housing at the ends thereof opposite where the first mentioned rod is located a bell crank pivotally mounted between its ends on said third rod and provided with bearing means to engage against said second mentioned rod whereby on operation of said bell crank in one direction, said bar is moved longitudinally and the spring thereon compressed and the bearing means on the latch bolt engaging against said rollers controls the pivotal movement of said latch bolt, as specified.

8. A construction as defined in claim 6, said bearing members carried by said latch bolt comprising circular disks with which said rollers have rolling contact.

LLOYD L. ANDERSON.
